UNITED STATES PATENT OFFICE.

WILLIAM WILBUR, OF COUNCIL BLUFFS, IOWA.

INTAKE-MANIFOLD VALVE LOCK.

Application filed April 10, 1922. Serial No. 551,029.

To all whom it may concern:

Be it known that WILLIAM WILBUR, citizen of the United States, residing at Council Bluffs, in the county of Pottawattamie and 5 State of Iowa, has invented certain new and useful Improvements in Intake-Manifold Valve Locks, of which the following is a specification, reference being had therein to the accompanying drawings.

10 The invention relates to valve locks used in connection with intake manifolds of internal combustion engines, and has for its object to provide a valve located in the intake manifold between the intake ports and 15 the carbureter and controlled by a lock operable from within the automobile and adjacent the instrument board.

A further object is to provide in combination with a pivoted disc valve located within 20 the intake manifold of an internal combustion engine carried by an automobile a casing extending through the instrument board and housing a plurality of longitudinal movable key actuated plungers for locking 25 the valve in closed position or allowing the valve to open.

With the above and other objects in view the invention resides in the combination and arrangement of parts as hereinafter set 30 forth, shown in the drawings, described and claimed, it being understood that changes in the precise embodiment of the invention may be made within the scope of what is claimed without departing from the 35 spirit of the invention.

In the drawings:—

Figure 1 is a side elevation of a portion of a conventional form of intake manifold and carbureter showing the device applied 40 thereto and showing the device partly in section and extending through a portion of the instrument board of the automobile body.

Figure 2 is an enlarged vertical longitudinal sectional view through the device.

Figure 3 is a transverse sectional view through the device taken on line 3—3 of Figure 1.

Figure 4 is a detail sectional view taken 50 on line 4—4 of Figure 2.

Referring to the drawing, the numeral 1 designates a conventional form of intake manifold which leads from the carbureter 2. Disposed in the intake manifold 1 is a 55 valve casing 3, through which products from the carbureter 2 pass to the cylinders of the

engine on the suction strokes of the pistons therein. Extending upwardly and rearwardly from the casing 3 is a cylindrical casing 4, in which casing 4 is rotatably 60 mounted a cylinder 5 to which is connected a disc valve 6 located within the chamber 7 of the valve casing 3. It will be noted that when the cylinder 5 is rotated the valve 6 may be placed to extend transversely across 65 the chamber 7 for cutting off the passage of gases from the carbureter 2 through the intake manifold. It will also be noted that the disc valve 6 may be positioned where it will allow gases to pass through the manifold. Threaded at 8 to the outer end of the casing 4 is a cylindrical casing 9, which has 70 its upper end secured by means of screws 10 to the forward side of the instrument board 11. The casing 9 forms means for 75 preventing unauthorized persons from tampering with the mechanism hereinafter set forth.

The cylindrical portion 5 is rotatably mounted in a bearing 12 in the casing 4, and 80 in a bearing 13 of the instrument board 11 is a tumbler cylinder 14, which houses spaced longitudinally movable tumblers 15. The tumblers 15 are slidably mounted in the bearings 16 of spacing members 17 disposed 85 within the cylinder 14. The lower ends of the tumblers are slidably mounted in bearings 18 of the cylindrical portion 5 carried by the cylinder 14 and which portion engages the disc 6^a of the valve 6. The tumblers 15 extending through the valve 6 and 90 register with spring actuated tumblers 6^b in the extension 6^c of the valve casing 3. The bearings 18 of the cylindrical portion 5 register with the bearings 20 of the valve 95 6 and receive the short plungers 6^b, which are forced inwardly by the springs 22 and are received in the bearings 20. When the valve 6 is locked in closed position as shown in Figure 1, the cylinder 5 and valve 6 100 are locked together to the valve casing 3 thereby preventing movement of the valve 6, and consequently preventing the passage of gas through the manifold and preventing unauthorized persons from starting the engine. Threaded into the outer end of the casing 4 is a bushing 23, which cooperates 105 with a packing 24 for preventing passage of water or foreign matter into the working parts of the lock.

Secured by means of screws 25 to the rear face of the instrument board 11 is a cas-

ing 26, in which casing the rear end of the cylinder 14 is rotatably mounted and prevented against rearward movement by engagement with the shoulder 27 of the casing 26. When it is desired to open the lock a key is passed through the key entrance 28 of the cylinder 14 and into engagement with the ends 29 of the tumblers 15, said key being so shaped that the lower ends of the tumblers 15 will be moved into registration with the lower side of the valve 6 thereby moving short tumblers 6^a into the valve casing extension and allowing the valve 6 to be opened by rotating the casing 14 by rotating the key. When it is desired to move the valve to locked position the key is placed through the key entrance 28 and the cylinder 14 rotated until the short plungers 6^a again enter the bearings 20 of the valve 6. The tumblers 15 are normally held in outer position as shown in Figure 2 by means of coiled springs 30 which surround the tumblers and are interposed between the spacing members 17 and pins 31, extending through the tumblers which pins engage the spacing members and limit the movement of the plungers.

From the above it will be seen that a locking mechanism is provided for a valve located in an intake manifold of an internal combustion engine, said mechanism being so constructed that the valve may be controlled from within the automobile, pref-

erably from the instrument board, although it may be from any other part of the automobile adjacent the operator's seat. It will also be seen that by cutting off the flow of gas from the carburetor to the engine, through the intake manifold that the engine cannot be started by cranking or through the self starter, thereby preventing theft of the vehicle.

The invention having been set forth what is claimed as new and useful is:—

The combination with a valve carried by the intake manifold of an internal combustion engine of a motor driven vehicle and an instrument board carried by said vehicle, of a lock for locking said valve in closed position, said lock being carried adjacent the valve, a tumbler casing rotatably mounted in a bearing of the instrument board and in a bearing of the manifold, longitudinally movable key actuated tumblers extending through said casing and through the valve, spring actuated tumblers carried in the manifold and registering with the longitudinal movable key actuated tumblers, said longitudinally movable key actuated tumblers being proportioned whereby the spring actuated tumblers will be moved longitudinally for releasing the valve.

In testimony whereof I hereunto affix my signature.

WILLIAM WILBUR.
